POSITIONING AND SUPPORTING DEVICE
FOR CAR COUPLERS

Garth G. Gilpin, Chicago, Ill., assignor to Standard Railway Equipment Manufacturing Company, Chicago, Ill., a corporation of Delaware

Application November 12, 1943, Serial No. 510,056

14 Claims. (Cl. 213—61)

1

This invention relates to improvements in railway cars and more particularly to improvements in means for supporting the outer end of a railway car coupler adjacent its "head."

My present invention is an improvement over Patent No. 1,923,433 granted to me on August 22, 1933, and Patent No. 2,308,032 granted to James S. Swann on January 12, 1932, both of which patents are assigned to the same assignee to which this invention and application will be assigned.

One of the objects of the invention is to support a railway car coupler upon a device which permits the coupler to move horizontally and vertically with the coupler of another car when coupled thereto as the couplers adjust themselves to the curves and unevenness of the track, as well as causes the coupler to return to normal coupling range when free to do so; for instance, when a coupler supported by my device is uncoupled while the railway car is upon a curved track.

Another object of the invention is to provide a resilient means in a carrier for supporting the outer end of a coupler at a desired elevation during service movements of the car, but which means permits downward and/or lateral movement of the coupler when an additional live load is applied such as when two coupled cars are pulled over a track elevation, hump, vertical curve in the track, or around a curve, and wherein said carrier, when free to do so, will return the coupler to its normal height and simultaneously to a position at least adjacent the center of the car within coupling range.

Another object of the invention is to reduce the service stresses in the coupler by providing a resilient coupler carrier thereby permitting the outer end of the coupler to move vertically so that the center line of coupled couplers will be nearer a straight line, thus reducing the resultant force in the coupler shank. When the force ceases, as when the cars are uncoupled, the resilient carrier returns the coupler to its normal vertical position, which is an essential in accepted railroad operation when coupling railway cars.

A further object of my improved resilient coupler support and coupler centering device is to prevent jar in the coupler, caused by uneven track and the movement of the coupler on the carrier, from being transmitted by the coupler to adjacent car parts, and furthermore, to reduce the friction and wear between the associated parts.

Another object is to provide a resilient means which cushions and centers the coupler by maintaining the carrier in adjustment with the cou-

2

pler, and which may be readily and quickly assembled or taken apart; is very light in weight and economical to manufacture.

Another object of the invention is to resiliently support the coupler by a pair of spaced apart springs and provide means so that as the coupler moves laterally a predetermined distance, in either direction, the springs will be distorted, thereby causing a tendency for the springs to return the coupler toward its normal position and within coupling range and at the same time arrange such means so that the coupler may move laterally (in either direction) beyond said predetermined position without further distorting the springs and at the same time not relieving the springs of any distortion. Such an arrangement may be necessary and advisable where the coupler moves a great distance laterally, such as in passenger train cars. The object of such construction is to limit the distortion of the springs as excessive and frequent distortions may cause fatigue of the metal and breakage of the spring. The distance two couplers are out of alignment and will still couple is called the coupling range.

Throughout the specification, wherever the term "coupler" is used, it is understood to mean a standard railway car coupler wherein no provision is made for the coupler to rotate around its longitudinal axis.

30 Also in the modifications of the invention some of the elements roll, some rock and some do both simultaneously, therefore, applicant has used in the specification and claims the word "rock" (and derivations thereof) with the understanding that, for the purpose of describing the invention, the term includes a rocking and/or rolling action.

In the drawings:

Fig. 1 shows the striking casting of a railway car with my device applied thereto.

Fig. 2 is a section on line 2—2 of Fig. 1.

Fig. 3 shows the coupler and my device in normal position; that is, adjacent the middle of the car.

Fig. 4 shows the coupler and the relative position of the component elements of my device when the coupler has been moved laterally a predetermined distance.

Fig. 5 is the same as Fig. 4 except that the coupler has been moved laterally more than said predetermined distance.

Fig. 6 shows a modification of the invention with the coupler in normal position.

Fig. 7 shows the modification with the coupler moved laterally a predetermined distance.

Fig. 8 shows the modification with the coupler

moved laterally more than said predetermined distance.

Fig. 9 is a perspective view of one end of the rocker showing the lower convolution of a spring thereupon in dotted lines.

The construction shown in Figs. 1 and 2 is diagrammatically illustrated in Figs. 3, 4 and 5, wherein the coupler 2 is normally positioned at the middle 3 of the car and is arranged to move in horizontal planes laterally and/or vertically of the car in service. The coupler rests upon a coupler carrier 4 which moves vertically with the coupler and the carrier is provided with lugs 5 on opposite sides of the coupler so that the carrier moves laterally, in either direction, with the coupler. A member 6 having a portion 7 below the coupler is fixed to the striking casting 8 by the bolts 9.

My improved device is positioned between the fixed member 6 and the coupler carrier 4 and supports the coupler 2 and carrier 4 upon the fixed member 6.

Fig. 3 shows the relative position of the coupler 2 and the several parts of my device when the coupler is in the normal position; that is, adjacent the middle 3 of the car.

My device comprises a spring seat 10 mounted upon the fixed member 6 by spaced supports 11-12 to rock laterally of the car and a spring cap 13 which is mounted upon the carrier by spaced supports 14-15 to rock laterally of the car and springs 18 interposed between the spring cap 13 and spring seat 10 and spaced equi-distant on opposite sides of the middle 3 of the car. The pivots 11-12 and 14-15, respectively, are preferably spaced equi-distant on opposite sides of the middle 3 of the car. In this position the springs resiliently support the coupler and the carrier and cushion the coupler against the service movements due to rough and uneven track.

Fig. 4 shows the position of the coupler 2, carrier 4 and associated parts of my device when the coupler has moved laterally toward one side of the car. In this position, due to the wide bearing; that is, the distance between the spaced apart supports 11-12 and 14-15, neither the spring seat 10 nor spring cap 13 will rock upon their respective supports so that the spring seat and spring cap will be held in parallel relationship and cause the springs 18 to be distorted, which distortion causes the springs to urge the carrier and the coupler toward central position; that is, at least to a position within coupling range. The coupler and carrier will thus be returned to coupling range when the coupler is free to so return which will be when the coupler is detached from the other coupler. Any desired means, such as the lugs 17, on the spring seat 10 and spring cap 13 may be used to hold the springs in place. In practice this will be about $\frac{1}{8}$ " lateral movement of the coupler.

Fig. 5 shows the coupler 2, carrier 4 and associated parts of my device when the coupler has moved beyond the above mentioned predetermined movement of about $\frac{1}{8}$ " to about $1\frac{3}{4}$ " which is the permissible movement in freight cars. When the coupler has been moved laterally from the position shown in Fig. 4 to the position shown in Fig. 5 the spring seat 10 has rocked upon the support 12 and the spring cap 13 has rocked upon the support 14, thus allowing the spring seat, spring cap and the springs to remain substantially as they are in Fig. 4; that is, without any substantial increase or decrease in the distortion of the springs. In other words, the

supports 11-12 and 14 and 15, being spaced apart, causes the springs to be delayed in their tilting or rocking action until the coupler has moved laterally beyond normal coupling range.

5 The projections 20-21 in the spring seat 10 and spring cap 13 hold the elements in proper operative relationship.

The member 6 may be fixed to the car in any desirable manner, and likewise, any desired construction may be used to restrict the downward movement of the coupler carrier, so as not to compress the springs too much and any construction may be used to restrict the movement of the coupler carrier lengthwise of the car though permitting said carrier to freely move laterally of the car. It is common practice to allow a carrier to swing laterally of the car between two walls which are fixed to the car, and arrange such walls to limit the downward movement of the carrier.

20 Figs. 6, 7 and 8 show a modified construction wherein the carrier 30 performs the functions of the spring cap so that a separate spring cap is not necessary and the spring seat is in the form of a rocker 31 which rocks upon the fixed member 6 when the coupler moves laterally. In the modification the carrier 30 is held in a horizontal position by the coupler as the coupler is moved laterally. When the coupler moves laterally a predetermined distance to the right (as shown in Fig. 7) the rocker 31 rocks upon the fixed member 6 and the left or trailing spring 32 is compressed while the right or leading spring 33 is neither compressed nor relieved to any appreciable extent, thus the left or trailing spring 32 urges the device to return to normal position.

35 The springs 32-33 are rockably mounted upon flat surfaces 35 on the carrier 30 and flat surfaces 36 on the spring seat 31 between oppositely inclined surfaces 38-39-40 and 41. The inclined surfaces are so shaped and positioned that until the coupler has moved a predetermined amount (as shown in Fig. 7) neither of the springs 32-33 is distorted, but upon further lateral movement of the coupler, the springs rock upon the edges 45 of the flat surfaces 35 and 36 and engage the inclined surfaces in the carrier and spring seat, respectively, at the opposite diagonal corners thereof, which distorts both of the springs, as shown in Fig. 8, thus providing an additional force to urge the device and coupler toward normal position. As the device moves from the position shown in Fig. 7 to that shown in Fig. 8 neither of the springs is further appreciably distorted. Any desirable means may be used to prevent the rocker 50 31 from slipping upon the fixed member 6.

55 The accompanying drawings illustrate the preferred form of the invention, though it is to be understood that the invention is not limited to the exact details of construction shown and described, as it is obvious that various modifications thereof, within the scope of the claims, will occur to persons skilled in the art.

60 In my application Serial No. 510,055, filed November 12, 1943, concurrently herewith, I have disclosed but not claimed certain features claimed herein.

I claim:

65 1. A cushioning coupler supporting and positioning device for a railway car coupler movable laterally and vertically of a car in substantially horizontal planes, said car having a member fixed to the car below the coupler; said device comprising a spring seat mountable upon said fixed member at spaced supports, a spring cap, a coupler carrier mountable upon said spring cap at spaced

supports, said coupler carrier adapted to move laterally and vertically with the coupler, and spaced springs adapted to be interposed between said spring seat and spring cap and on opposite sides of said spaced supports, whereby when the device is applied to a car and the carrier is moved laterally a predetermined distance by the coupler the spring seat and spring cap are held in parallel relationship by said spaced supports and the springs are laterally distorted, said distorted springs providing a restoring force urging the device toward coupling range and whereby upon further lateral movement of the coupler the spring seat, springs and spring cap rock as a unit upon one of said supports without substantially further distorting the springs.

2. A coupler cushioning, positioning and supporting device for a railway car coupler movable laterally and vertically of a car in substantially horizontal planes, a coupler carrier to support said coupler and move therewith, and a member fixed to the car below the coupler; said device comprising spaced springs adapted to resiliently support the carrier, means including a spring seat mountable upon said member to support said springs upon said member upon spaced supports between said springs when the device is applied to a car, said springs being laterally distorted upon a predetermined lateral movement of the carrier, thus providing a restoring force in the springs to return the carrier to normal central position when free to do so and further lateral movement of the carrier will cause said spring seat to rock upon one of said supports without further distortion of the springs.

3. A cushioning coupler supporting and positioning device for a railway car coupler movable laterally and vertically of a car in substantially horizontal planes, which car is provided with a part having a portion below the coupler; said device comprising resilient means adapted to resiliently support said coupler, and means including a spring seat upon said portion adapted to support said resilient means upon said portion when the device is applied to a car, said supporting means formed and operatively associated with said coupler and portion, respectively, so that a predetermined lateral movement of the coupler will distort said resilient means, and further lateral movement of the coupler will not relieve nor further distort said resilient means, thus providing a restoring force in the distorted resilient means to return the coupler to coupling range.

4. A cushioning and positioning device to support a coupler carrier upon a member fixed to a railway car, which carrier is movable vertically and laterally of the car in substantially horizontal planes; said device comprising a spring seat, a spring cap, and spaced springs adapted to be interposed therebetween, means adapted to support said device between said carrier and member, respectively, at spaced points between said springs when the device is applied to a car, said springs being laterally distorted during movement of the carrier laterally of the car a predetermined distance, thus providing a restoring force in said springs to return the carrier to normal position when free to do so, and further lateral movement of the carrier will cause said device to rock about one of said points without further distortion of the springs.

5. A cushioning coupler supporting and positioning device for a railway car coupler, said coupler mounted normally adjacent the middle of a railway car and arranged to move vertically

and/or laterally of the car in substantially horizontal planes, said car having a member fixed below the coupler; said device comprising a carrier for supporting the coupler, said carrier adapted to move vertically and/or laterally with the coupler, a spring seat so formed as to be rockable upon said member fixed to the car; and spaced springs adapted to be interposed between said carrier and said spring seat substantially equi-distant on opposite sides of the middle of the car when the device is applied to a car, said carrier and spring seat being so formed that said springs are rockably mounted upon the carrier and spring seat, respectively, on a relatively wide flat surface between oppositely inclined surfaces, said flat surfaces and said inclined surfaces being positioned in relation to each other and to said springs so that as the carrier is moved laterally a predetermined distance both springs are distorted and the trailing spring is compressed more than the leading spring, thus providing a restoring force in said springs for urging the carrier toward normal central position, and a further lateral movement of the carrier will cause each spring to rock from said flat surface to one of said inclined surfaces without further distortion.

6. A coupler cushioning and positioning device for a railway car coupler mounted upon a car to move in substantially horizontal planes laterally and vertically within a support having a member below the coupler; said device comprising spaced springs adapted to resiliently support the coupler, and means including a spring seat upon said member adapted to support said springs upon said member at spaced points between said springs, said springs and support operatively associated with said coupler and member, respectively, when the device is applied to a car, said springs being laterally distorted upon a predetermined lateral movement of the coupler within coupling range, thus providing a restoring force in the springs to maintain the coupler within normal coupling range, and further lateral movement of the coupler will cause the support to rock about one of said spaced points without further distortion of the springs.

7. A cushioning coupler supporting and positioning device for a railway car coupler movable laterally and vertically of a car in substantially horizontal planes, which car is provided with a part having a portion below the coupler; said device comprising spaced springs adapted to resiliently support said coupler, and a support mountable upon said portion for said springs, said support having spaced flat surfaces, each between oppositely inclined surfaces, said springs normally resting upon said flat surfaces, when the device is applied to a car, said flat surfaces and said inclined surfaces being positioned relative to each other and to said springs so that as the coupler is moved laterally a predetermined distance both springs are distorted, and a further lateral movement of the coupler will cause each spring to rock from said flat surface to one of said inclined surfaces without relieving or further distorting said springs, thus providing a restoring force in the distorted springs to return the coupler to coupling range.

8. A cushioning coupler supporting and positioning device for a railway car coupler movable laterally and vertically of a car in substantially horizontal planes, which car is provided with a part having a portion below the coupler; said device comprising tiltable spaced springs adapted to resiliently support the coupler, and means in-

cluding a spring seat upon said portion adapted to tiltably support said springs upon said portion, at spaced points between said springs, when the device is applied to a car so that said springs are laterally distorted upon a predetermined lateral movement of the coupler within coupling range, thus providing a restoring force in the springs to maintain the coupler within normal coupling range when free to do so, and further lateral movement of the coupler will cause the tiltably support to tilt upon one of said spaced points without further distortion of the springs.

9. A cushioning coupler supporting and positioning device for a railway car coupler movable laterally and vertically of a car in substantially horizontal planes, which car is provided with a part having a portion below the coupler; said device comprising spaced springs adapted to resiliently support the coupler, and means including a spring seat mountable upon said portion to support said springs upon said portion, at spaced points between said springs, when the device is applied to a car so that said springs are laterally distorted upon a predetermined lateral movement of the coupler within coupling range, thus providing a restoring force in the springs to maintain the coupler within normal coupling range when free to do so, and further lateral movement of the coupler will cause the support to rock upon one of said spaced points without further distortion of the springs.

10. A cushioning coupler supporting and positioning device for a railway car coupler movable laterally and vertically of a car in substantially horizontal planes, which car is provided with a part having a portion below the coupler; said device comprising a coupler carrier adapted to support said coupler and move laterally and vertically therewith, tiltably spaced springs adapted to resiliently support said carrier, and means adapted to tiltably support said springs upon said portion, at spaced points between said springs, when the device is applied to a car so that said springs are laterally distorted upon a predetermined lateral movement of the carrier within coupling range, thus providing a restoring force in the springs to maintain the coupler within normal coupling range when free to do so, and further lateral movement of the carrier will cause the support to tilt upon one of said spaced points without further distortion of the springs.

11. A cushioning coupler supporting and positioning device for a railway car coupler movable laterally and vertically of a car in substantially horizontal planes, which car is provided with a part having a portion below the coupler; said device comprising a coupler carrier adapted to support said coupler and move laterally and vertically therewith, spaced springs adapted to resiliently support said carrier, and means adapted to support said springs, upon said portion, said carrier and said means having surfaces providing a delayed tiltably engagement with said springs when the device is applied to a car so that said springs are laterally distorted upon a predetermined lateral movement of the coupler within coupling range, thus providing a restoring force, the springs to maintain the coupler within normal coupling range when free to do so and said surfaces providing spaced points about either of which said means may rock and thereby permit

further lateral movement of the coupler beyond coupling range without further distortion of said springs.

12. A cushioning coupler supporting and positioning device for a railway car coupler movable laterally and vertically of a car in substantially horizontal planes, which car is provided with a part having a portion below the coupler; said device comprising a coupler carrier adapted to support said coupler and move laterally and vertically therewith, tiltably spaced springs adapted to resiliently support said carrier, and means adapted to support said springs, said means tiltably supported upon said portion, said carrier and said means having surfaces providing a delayed tiltably engagement with said springs when the device is applied to a car so that said springs are laterally distorted upon a predetermined lateral movement of the coupler within coupling range, thus providing a restoring force in the springs to maintain the coupler within normal coupling range when free to do so and said surfaces providing spaced points about either of which said means may rock and thereby permit further lateral movement of the coupler beyond coupling range without further distortion of said springs.

13. A cushioning coupler supporting and positioning device for a railway car coupler movable laterally and vertically of a car in substantially horizontal planes, which car is provided with a part having a portion below the coupler; said device comprising a spring cap, spaced springs adapted to resiliently support said spring cap, a spring seat adapted to tiltably support said springs upon said portion, said spring seat having a surface providing a delayed tiltably engagement with said portion when the device is applied to a car so that said springs are laterally distorted upon a predetermined movement of the coupler within coupling range, thus providing a restoring force in the springs to maintain the coupler within normal coupling range when free to do so and said surface also providing spaced points about either of which said spring seat may rock and thereby permit further lateral movement of the coupler beyond coupling range without further distortion of said springs.

14. A cushioning coupler supporting and positioning device for a railway car coupler movable laterally and vertically of a car in substantially horizontal planes, which car is provided with a part having a portion below the coupler; said device comprising a coupler carrier adapted to support said coupler and move laterally and vertically therewith, tiltably spaced springs adapted to resiliently support said carrier, and means adapted to be rockably supported upon said portion, said carrier and said means having opposed surfaces providing a delayed tiltably engagement with said springs when the device is applied to a car so that said springs are laterally distorted upon a predetermined lateral movement of the coupler within coupling range, thus providing a restoring force in the springs to maintain the coupler within normal coupling range when free to do so, and said surface also providing spaced points about either of which said spring seat may rock and thereby permit further lateral movement of the coupler beyond coupling range without further distortion of said springs.

GARTH G. GILPIN.
